COOKING DEVICE

William H. Wiggins, 137 Willowdale Ave.,
Toronto, Ontario, Canada

Filed May 26, 1969, Ser. No. 17,333

Term of patent 14 years

The portion of the term of the patent subsequent to
Aug. 27, 1982, has been disclaimed

Int. Cl. D7—02

U.S. Cl. D81—10

FIG. 1

FIG. 2

FIG. 3

FIG. 1 is a perspective view of the cooking device in open position;

FIG. 2 is a side elevation of the cooking device in open position drawn to a smaller scale; and

FIG. 3 is a side elevation similar to FIG. 2 showing the article in closed position. The arrows in FIGS. 2 and 3 are intended to indicate that the handle swings independently of the cover.

I claim:

The ornamental design for a cooking device, as shown and described.
